UNITED STATES PATENT OFFICE.

THEODORE C. PROUTY AND WILLIS O. PROUTY, OF HERMOSA BEACH, CALIFORNIA.

ELECTRIC KILN.

Application filed June 27, 1927. Serial No. 201,809.

Our invention is an improvement in electrically heated tunnel kilns and has for its principal object the disposition of the heating elements in such manner as to apply the radiated heat to the ware being fired with minimum loss through the walls of the kiln. In order to accomplish this purpose we mount the heating elements upon the movable platform which carries the ware through the kiln and in close proximity to the ware whereby only a negligible amount of heat is radiated to the tunnel walls. Substantially all of the radiant energy is absorbed by the ware, the only heat conveyed to the tunnel walls being that carried thereto by the heated air in the tunnel space. In the drawings:

Figure 1 is a transverse section of a tunnel kiln embodying our invention.

Figure 2 is a fragmentary sectional view on plane 2—2 of Figure 1.

Figure 3 is a fragmentary sectional view on plane 3—3 of Figure 1.

Figure 4 is a perspective view of one of the contact brushes carried by the heating elements.

We have illustrated the invention as applied to a kiln of the type shown in Patent No. 1,613,054, granted January 4, 1927, but it may be adapted to tunnel kilns employing cars or other means to move the ware. The walls 1 of the kiln are constructed to prevent as far as possible the loss of heat by conduction, and the inner surfaces of the walls will preferably be glazed to prevent transmission of radiant heat as described in co-pending application of Willis O. Prouty executed June 18, 1927. As described in the prior patent above referred to, the kiln is provided with a floor 2 of vitrified refractory material, upon which rest and slide the plates 3, suitable means being provided, as described in said previous patent, to propel the plates through the tunnel.

At intervals narrow plates 4, preferably somewhat thicker than plates 3 are placed between adjoining plates 3 to serve as bases for the upright supports 5 upon which the heating elements 6 are wound or otherwise supported. It will be understood, of course, that the heating elements 6 may be constructed of any of the resistance metals or alloys suitable for the purpose and that the other parts described are formed of suitable refractory material. We have shown the resistance wire 6 as wound in helical form

through perforations in the supporting plate 5, though other arrangements of the heating element upon its support might be employed. The outer edges of the floor of the tunnel are elevated as indicated at 9 and 10 forming guides between which the plates 3, 4 move through the center of the tunnel equidistant from the side walls. The plates 5 upon which the heating elements 6 are supported may be inserted in grooves in the plates 4 as shown in the drawing.

The conductors or bus wires for supplying current to the heating elements 6 may be mounted in grooves extending longitudinally along the upper surfaces of the elevated floor sections 9, 10. The opposite ends of each heating element are outwardly turned as indicated at 7, 8 to overhang the bus wires 12, 11, and carry brushes 14, 15 which bear upon the bus wires. These brushes may take the form of strips bent at one end to embrace the overhanging end of the electrical element and at the other curved to drag smoothly over the bus wire as shown in Figure 4. A weight 15 may be placed upon each of the brushes to insure close contact with the underlying bus wire.

As indicated in Figure 3 the bus wires may be in detached sections 11, 11, and the pairs of wires in each section upon opposite sides of the kiln may be in separate circuits carrying different voltages. As the conveyor units 3, 4 move through the kiln the brushes 14, 15 of each of the several heating elements will contact successively with the bus terminals of the several circuits and by arranging the successive circuits with gradually rising voltages the ware may be properly preheated and gradually brought to the maximum firing temperature, and if desired the cooling may be retarded by providing one or more following circuits carrying current at a lower potential.

We claim:

1. In a tunnel kiln, a conveyor for moving ware therethrough, electrical heating elements mounted upon said conveyor, and means for supplying electric current to said elements while moving through said kiln.
2. In a tunnel kiln, a conveyor for moving ware therethrough, electrical heating elements mounted on said conveyor, electrical contact members mounted in the tunnel space of the kiln and means for establishing contact between the terminals of said heating elements and said contact members.

3. In a tunnel kiln, a conveyor for moving ware therethrough, electrical heating elements mounted on said conveyor, electrical contact members mounted in and extending longitudinally of said kiln, and terminals upon said heating elements adapted to establish electrical connection with said contact members during the movement of said elements through said tunnel.
4. In a tunnel kiln, a conveyor for moving ware therethrough, electrical heating elements mounted on said conveyor, and a plu-

rality of pairs of electrical contact members mounted in and extending longitudinally of said kiln, and terminals upon said heating elements adapted to establish electrical connection successively with said pairs of contact members during the movement of said elements through said tunnel.

In testimony whereof, we have subscribed to our names.

THEODORE C. PROUTY.
WILLIS O. PROUTY.
